(74) Attorney, Agent, or Firm — Albert Bordas, P.A.

(57) **CLAIM**

The ornamental design for a bib with adhesive neckline, as shown and described.

DESCRIPTION

FIG. 1 is a top plan view of a bib with adhesive neckline; FIG. 2 is a front elevational view thereof; FIG. 3 is a bottom view thereof; FIG. 4 is a left-side elevational view thereof, the right-side elevational view being a mirror image thereof; FIG. 5 is a rear elevational view thereof; FIG. 6 is a front isometric view thereof, and, FIG. 7 is a rear isometric view thereof.

The claimed bib with adhesive neckline is used for the collection of liquids, semi-solid and/or solid materials during the application or removal of makeup; keeping wipes, tissues, napkins or any other personal hygiene supplies in an internal pocket that can be folded to a front side according to the user's convenience.

1 Claim, 4 Drawing Sheets
